S. N. STEWART.

WICKET OR ARCH FOR PLAYING CROQUET AND THE LIKE.

APPLICATION FILED OCT. 3, 1918.

1,299,055.

Patented Apr. 1, 1919.

Inventor:

Sylvester N. Stewart,

*by Dear Middleton, Daniels and Spear
Atty's.*

UNITED STATES PATENT OFFICE.

SYLVESTER N. STEWART, OF MARIETTA, OHIO.

WICKET OR ARCH FOR PLAYING CROQUET AND THE LIKE.

1,299,055.

Specification of Letters Patent.

Patented Apr. 1, 1919.

Application filed October 3, 1918. Serial No. 256,735.

To all whom it may concern:

Be it known that I, SYLVESTER N. STEWART, a citizen of the United States, and resident of Marietta, Ohio, have invented certain new and useful Improvements in Wickets or Arches for Playing Croquet and the like, of which the following is a specification.

The invention has for one of its objects to 10 increase the visibility of the arch or wicket and is adapted for use in daylight playing or in the dusk of evening, or at night, when there is little light.

Another object of the invention is to increase the accuracy of the player's strokes 15 by providing a target so positioned in relation to the wicket or arch as will enable the player to aim his shots toward the center line of the wicket.

20 My construction also enables me to provide a wicket of economical construction, and one which will enable the structure to maintain its shape at its upper portion and will also facilitate the placing of the wicket 25 in the ground.

The invention consists in the features and combination and arrangement of parts hereinafter described and particularly pointed out in the claims.

30 The drawing shows a perspective view of a wicket or arch built according to my invention.

The wicket is made of wire or rod shaped material having its upper or arch portion 35 reinforced by a member 1, which may consist of a block of wood, or piece of board, having openings near its ends at 2 extending vertically therethrough to receive the legs or sides 3 of the wire arch. The upper 40 transverse portion of the wire arch may fit close along the upper edge of the board or block as indicated. The target may consist of a spot painted on both sides of the board centrally over the space between the sides 45 or legs of the wicket and this spot may be of circular form, as shown, or any other desired form.

As above stated the game may be played after dark, the white bull's-eye serving to 50 increase the visibility of the wicket as well

as answering as a target toward which the players may make their strokes.

Candles have been employed heretofore, surmounting a wicket, but the white bull's-eye saves the cost of candles and avoids the 55 objections existing thereto, arising from the candle grease smearing the wickets and avoiding the annoyance resulting from blowing out of the candles.

The target stiffens the arch, keeps it in 60 shape, adds to the appearance and durability and also serves as a handle with which to push the arch into the ground.

In addition to the bull's-eye placed on the head or board at the top of the wicket I also 65 prefer to enamel the ends of this block or board with white material so that a player approaching the target from the side can make his stroke accurately. The player may be in such a position that the target 70 on the front or back of the block cannot be seen but with the ends of the block painted or enameled white he will be able to determine the direction that his stroke should be made. 75

Of course the bull's-eye together with the ends of the board may be supplied with a disk or sheet of metal or thin wood set into a slight depression in the block or board and this disk or sheet may be painted or enameled white as above mentioned. 80

What I claim is:

1. A wicket for playing croquet or the like consisting of a wire member having legs and a cross portion at the top thereof 85 and a target member connecting the legs at the upper part thereof below the cross portion, substantially as described.

2. A wicket consisting of a wire member having legs and a cross portion at the top 90 and a board or block mounted on the wire legs beneath the cross portion and having a target carried thereby, substantially as described.

3. In combination with the wire member 95 having the legs and the upper cross portion, a board or block having openings receiving the wire member and located below the cross portion, substantially as described. 100

4. A wicket comprising the legs and the substantially straight cross piece at the upper ends thereof and a board or block connecting the legs and located close below the straight cross piece, substantially as described.

5. A wicket consisting of a wire member having legs and a cross portion at the top

and a board or block mounted on the wire legs beneath the cross portion and having a target carried thereby substantially centrally of the face thereof, the end faces of the board also having targets, substantially as described.

In testimony whereof, I affix my signature. 15
SYLVESTER N. STEWART.
